United States Patent Office

Des. 194,375
Patented Jan. 8, 1963

194,375

PACKAGING TRAY FOR BAKERY PRODUCTS

George V. Malmgren, Jr., Blue Island, Ill., assignor to Malanco Plastics, Inc., Blue Island, Ill., a corporation of Illinois

Filed Mar. 1, 1962, Ser. No. 69,037

Term of patent 14 years

(Cl. D58—13)

Fig. 1.

Fig. 2.

Fig. 3.

FIGURE 1 is a top plan view of a packaging tray for bakery products illustrating my new design;

FIGURE 2 is a side elevational view thereof; and

FIGURE 3 is an end elevational view thereof.

I claim:

The ornamental design for a packaging tray for bakery products, as shown.

References Cited in the file of this patent

UNITED STATES PATENTS

D. 110,640	Havekost	July 26, 1938
D. 169,220	Polglase	Mar. 31, 1953
1,669,057	Katzinger	May 8, 1928